APPARATUS FOR WASHING DISHES,
SILVERWARE, AND THE LIKEDonald E. Yochem, Columbus, Ohio, assignor to
L. S. D., Inc., Dayton, Ohio, a corporation of
Ohio

Application November 2, 1939, Serial No. 302,594

9 Claims. (Cl. 299—63)

This invention relates to new and useful improvements in apparatus for washing, rinsing and drying dishes, silverware, and the like and is a modification of the apparatus disclosed and claimed in my Patent No. 2,137,971, issued November 22, 1938. More specifically, this invention relates to fluid impelling mechanism which is adapted to be employed in place of the impelling mechanism disclosed in my aforesaid patent.

In the above-referred to patent there is disclosed fluid impelling mechanism which is designed to disperse at a high velocity a finely atomized fluid in such a way that all portions of the entire interior of the treatment housing will simultaneously receive the fluid. Although this patented apparatus is intended to be operated with an unusually small amount of liquid, as compared to other dish washing machines obtainable on the open market, it has been discovered that dishes, and the like, can be more effectively and just as quickly treated with even a smaller quantity of liquid if the zone treated at any given instant is reduced to a fractional portion of the total area of the housing and if the treatment zone is continuously moved during the operating period of the apparatus so that all portions of the interior of the housing repeatedly will fall within or form a part of the treatment zone. As the normal operating cycle of machines of this type involves charging the housing twice with hot water for each batch of dishes, or the like, being treated, the first charge being for washing and the second charge for rinsing, any appreciable reduction in the amount of hot water used results in a considerable saving in the cost of heating the water when the apparatus is employed in lunchrooms, soda fountains, restaurants, tap rooms, or the like, where batch after batch of dishes, silverware and glasses must be cleaned during rush periods.

It is a primary object of this invention to provide fluid impelling mechanism for dish washing machines, of the type where the treatment fluids are collected in and dispersed from a trough formed in the bottom of the housing by an impeller which rotates about a horizontal axis, wherein the dispersed fluid is concentrated in a zone which covers only a fractional portion of the interior of the housing and the treatment zone is continuously moved back and forth relative to the housing so that all portions of the housing will be repeatedly included in the moving treatment zone.

A further important object of the invention is to provide novel means for continuously moving

or shifting the concentrated discharge of finely atomized fluid dispersed at a high velocity from a collecting trough by a rapidly rotating impeller.

Other objects and advantages of the invention will be apparent during the course of the following description.

In the accompanying drawings forming a part of this specification and in which like numerals are employed to designate like parts throughout the same.

Figure 1 is an end elevational view of the housing of a dish washing, rinsing and drying machine embodying this invention.

Figure 2 is a detailed, fragmentary, horizontal sectional view taken on line 2—2 of Fig. 1,

Figure 3 is a detail view taken on the line 3—3 of Fig. 2 and discloses part of the mechanism in vertical section and part in elevation, and

Figures 4, 5 and 6 are detail vertical sectional views illustrating respectively, the extreme lower position, the intermediate position and the extreme upper position of a deflector employed for changing the direction of discharge of the stream of finely atomized treatment fluid which is dispersed throughout the interior of the housing.

In the drawings, wherein for the purpose of illustration is shown the preferred embodiment of this invention, the reference character 10, in Fig. 1, designates in its entirety the housing for the dish washing, rinsing and drying machine embodying this invention. This housing is made up of the main body portion 11, supported on suitable legs 12 at its four corners, and a removable cover 13.

As disclosed in Figs. 2 and 4 to 6 inclusive, the main body portion 11 of the housing is formed by a bottom wall 14, having a shallow trough 15 formed therein and extending longitudinally of the housing with the trough being of curved or arcuate shape in vertical section, end walls 16 and 17 and side walls 18 and 19.

Suitable means, not shown, may be provided for delivering treatment fluid to the interior of the housing 10 and for withdrawing the fluid after the washing and rinsing operations have been performed. Such fluid discharging and feeding mechanism is illustrated in my aforementioned patent.

As is clearly illustrated in Fig. 2, the end walls 16 and 17 of the body portion 11 are provided with bearing openings 20 and 21 which are axially aligned. These openings are provided to allow for the insertion of bearing members 22 and 23 respectively which are secured in place by flanges 24 and 25 that may be bolted, riveted, or other-

wise secured to the end walls 16 and 17 respectively. These bearings each provide both internal and external bearing surfaces for purposes to be explained as the description proceeds. Although these bearings are illustrated as being of solid, block construction and as providing plane bearing surfaces, it is to be understood that these bearings may take numerous forms and may be anti-friction bearings if desired, just so they will accomplish their intended dual supporting function.

Journalized within the axially aligned bearing openings of the bearings 22 and 23 is an impeller shaft 26. This shaft has one end projecting beyond the bearing 22 to be connected by means of a coupling 27 to the armature shaft of an electric motor 28 which is supported on the end wall 16 of the housing by means of a mounting bracket or platform 29.

As is clearly illustrated in Figs. 2 and 4 to 6 inclusive, the impeller shaft 26 is positioned off-center, or eccentrically with respect to the transverse center of the trough 15. In other words, the impeller shaft 26 is located closer to the discharge side 30 of the trough 15 than to the fluid return side 31. Rigidly secured to the impeller shaft 26 at suitable, axially spaced intervals, are the impeller wheels 32. Each one of these wheels consists of a hub portion 33 and a suitable number of radially extending, longitudinally curved impeller blades 34.

By inspecting Figs. 4 to 6 inclusive, it will be seen that the impeller blades 34 are of proper length, relative to the distance between the impeller shaft 26 and the bottom of the trough, to cause the impeller blades to dip into the trough and expel the treatment fluid 35 therefrom. The impeller shaft, and its impeller wheels 32, rotate in a clockwise direction, as viewed in Figs. 4 to 6 inclusive, and the stream 36 of finely atomized fluid, traveling at a high velocity discharged from the side 30 of the trough 15 will have a length substantially equal to the length of the trough and will be substantially fan-shape in vertical section.

The elevation or level of the trough at the discharge side 30 determines the direction of discharge of this horizontally elongated, vertically fan-shaped stream 36. Fig. 4 illustrates the direction of discharge of the stream directly over the discharge side or edge 30 of the trough. When discharged in this manner, the stream 36 will treat objects located in the lower left hand corner portion of the housing. To change this direction of discharge of the stream 36, a vertically curved deflector blade 37 has been provided and is oscillatably associated with the discharge side 30 of the trough. This deflector blade is carried at its opposite ends by the arms 38 which in turn are secured to rings 39 journalized exteriorly on the bearings 22 and 23. Fig. 2 clearly illustrates this deflector blade 37 as extending substantially the full length of the trough 15. The deflector blade 37 is illustrated in Fig. 4 in its extreme lower or inner position where it is entirely housed within the trough 15. The discharge of fluid, when the deflector blade 37 is in this retracted position, is substantially over the discharge side or edge 30 of the trough. As the deflector blade moves outwardly of the trough, the upper edge of the blade acts as an extension of the discharge side 30 of the trough and changes the direction of discharge of the fluid stream 36. When the deflector blade 37 is in its intermediate position, as illustrated in Fig. 5, 75

the stream 36 will cover an area or zone which starts approximately from the plane at which the stream 36 in Fig. 4 terminates and extends around the periphery of the impeller wheels so as to include in its path all of the upper portion of the housing and the upper parts of the side walls of the main body and cover of the housing. As the deflector blade 37 moves still further in a clockwise direction, as viewed in Figs. 4 to 6 inclusive, it reaches its limit of outward movement, as illustrated in Fig. 6. The deflector blade 37, when in this position, functions to extend the discharge side or edge 30 of the trough a distance equal to the width or vertical height of the deflector blade. In Fig. 6, the stream 36 is illustrated as covering an area which will include substantially all of the side wall 19 of the housing, the overlying side wall of the cover 13, and a part of the top wall of this cover. It will be seen, therefore, that the entire interior of the housing will fall within the path or discharge zone of the stream 36 during one complete oscillation or stroke of the deflector blade 37 in one direction. Of course, as the blade returns from its extreme outer position of Fig. 6 to its extreme inner or retracted position of Fig. 4, the stream 36 will traverse the interior of the housing in the reverse direction. By continuously or repeatedly oscillating the deflector blade 37 between its two extreme positions, the entire interior of the housing will repeatedly fall within the discharge or treatment zone of the stream 36 and all articles arranged within the housing will be repeatedly subjected to the treatment fluid.

Of course, this deflector blade or trough extension may be manipulated manually if desired, but to obtain the most efficient, uniform treatment of all objects arranged throughout the entire interior of the housing, it has been found to be highly desirable to continuously oscillate the deflector blade during the entire period of operation of the impeller shaft 26 with its impeller wheels 32. To accomplish this continuous operation or oscillation of the deflector blade, an arm 40, see Figs. 2 and 3, project laterally of one of the deflector blade supporting arms 38 and extends through an arcuate slot 41 formed in the end wall 16 of the housing body 11. A pitman 42 is pivotally connected to the arm 40 at one end and is pivotally connected at its remaining end to an eccentric or crank pin 43 carried by a disc or crank arm 44 which is attached to the armature shaft 45 of a small, low speed motor 46. A cap or housing 47 is provided to enclose the crank disc 44, its crank pin 43, the pitman 42, and the projecting portion of the arm 40, as is clearly illustrated in Figs. 1 to 3. Although the deflector blade 37 may be caused to oscillate at any desired speed, it has been found to be most effective if the blade completes eight oscillations in each direction per minute. The small electric motor 46, therefore, should be of a type which will rotate its armature eight complete revolutions per minute. Of course, a higher speed small motor may be employed with speed reducing gearing which will drive the disc or crank 44 at the desired low speed although the armature shaft for the motor 46 operates at a much higher speed. Likewise, a suitable speed reduction drive may be interposed between the armature shaft of the motor 28 and the shaft which is employed for supporting the crank or disc 44. These modifications will be obvious to any person skilled in the art.

Certain factors have been found to be very

critical in connection with this fluid impelling mechanism. For example, for a housing which is sixteen inches in width, twenty-one inches in length and about fourteen inches in height, approximately three quarts of treatment fluid should be employed. The electric motor 28 should have an R. P. M. of about 3500. The impeller wheels should be spaced from approximately one-half inch to approximately one and one-half inches from each other and the best results are obtained when they are spaced approximately one inch apart. A clearance of from $\frac{1}{2}$ to $\frac{1}{8}$ of an inch should be provided between the tips of the impeller blades 34 and the curved inner surface of the deflector blade 37 to obtain the most efficient dispersion of fluid from the trough 15.

With the impeller wheels spaced in accordance with the range given above, it has been determined that the stream 36 is solid and of substantially uniform density throughout its entire length, or throughout the entire length of the trough. This is due to the fact that the impeller wheels, operating at the high speed of approximately 3500 R. P. M. will not only directly pick up fluid from the trough and discharge the same from their extremities but fluid will be picked up from the trough in the spaces between the impeller wheels and will be carried around with the wheels and discharged with the fluid leaving the extremities of these impeller blades. It has been determined, also, that a certain amount of side slip occurs on the advance faces of the impeller blades which causes some of the fluid actually picked up by the blades to move laterally of the advancing surfaces of the blades into the spaces between the blades and this fluid in the spaces between the blades which result from side slip from the advance surfaces of the blades will be discharged radially with the fluid leaving the extremities of the blades.

Figs. 4 to 6 inclusive illustrate the approximate depth of the treatment fluid in the different portions of the bottom of the housing during high speed operation of the impeller wheels. Of course, when the impeller wheels are idle, the fluid will reach a common level throughout the entire bottom of the housing.

As the return side 31 of the housing is entirely open or unobstructed during all periods of operation of the apparatus, any fluid which drops onto the portion of the bottom wall 14 of the housing arranged between the side wall 19 and the side 31 of the trough will readily flow back into the trough. Fig. 2 discloses the fact that the deflector blade 37 does not extend the entire distance between the end walls 16 and 17. Therefore, a certain amount of the liquid deposited on the bottom wall 14 of the housing between the side wall 18 and the discharge side 30 of the trough will be permitted to run back into the trough around the ends of the deflector blade 37 even when this blade is in its extreme upper position. The outer or under surface of the deflector blade 37, also, is not positioned relative to the top surface of the trough 15 so as actually to rub or contact the same. There is a certain amount of clearance left between these surfaces of the deflector blade and the trough and this clearance allows for the remainder of the water deposited to the left of the trough, or outwardly of its discharge side 30, to return to the trough beneath the deflector blade 37. This return of fluid beneath the deflector blade will in no way interfere with the discharge of fluid over the

inner or top surface of the deflector blade and from the upper edge of the same.

The dishes, silverware, and glassware to be washed, rinsed and dried may be supported in the housing 10 by means of the rack structure disclosed in my aforementioned patent or by means of the rack structure disclosed and claimed in my copending application Serial No. 210,937, filed May 31, 1938. Of course, other rack structures than those referred to above may be provided if desired.

In operating the mechanism disclosed and described above, the dishes, silverware, and glassware to be washed, rinsed and dried are positioned within the housing 10. The desired amount of hot water and a cleaning powder or fluid are delivered to the housing. The motors 28 and 46 are then started, after the cover 13 is applied, and the articles within the housing are subjected to treatment with the washing fluid. It has been determined that three minutes constitutes a very effective washing period. After the articles have been thoroughly washed, the wash water is drained from the housing and clear hot water is provided. This hot water is dispersed through the housing in the same manner as the washing fluid. A very brief rinse period is needed and may be from one-half to one minute. After the articles are thoroughly rinsed, the rinse water is drained from the housing. The movements of the impeller blades and the deflector blade are continued after the rinse water has been withdrawn from the housing, to circulate the air within the housing. This circulation of air plus the fact that the articles have been heated by the hot washing and rinsing fluids, very quickly dries the articles. The motors 28 and 46 then may be stopped, the cover 13 removed, and the wishes withdrawn from the housing, either by removing the dishes from the supporting rack, not shown, or by removing the rack with the dishes, etc., supported therein.

It is to be understood that the form of this invention herewith shown and described is to be taken as a preferred example of the same and that various changes in the shape, size, and arrangement of parts may be resorted to without departing from the spirit of the invention or the scope of the subjoined claims.

Having thus described the invention, I claim:

1. A dish and silverware washing, rinsing and drying machine comprising a housing having a shallow trough in the bottom wall thereof, an impeller shaft journaled in the housing above said trough, a series of axially spaced impeller wheels having radial blades fixed to said shaft, the blades being of proper length to dip into said trough, means for rotating said shaft at a sufficiently high rate of speed as to cause the impeller blades to expel fluid in a finely atomized condition from one side of the trough, said expelled fluid being in the form of a stream which is substantially equal in width to the length of the trough and is substantially fan-shaped in vertical section, a deflector oscillatably associated with said discharge side of the impeller and being operable to change the direction of discharge of said stream, and mechanical means for continuously oscillating said deflector in an arc substantially concentric with the path of the impeller blades to cause a stream of substantially uniform concentration to be repeatedly discharged back and forth in the housing interior.

2. A dish and silverware washing, rinsing and drying machine comprising a housing, a shallow

trough in the bottom thereof, alined bearings carried by the end walls of the housing above said trough, a bladed impeller shaft journaled into said bearings, the blades being of proper length to dip into said trough, means for rotating said impeller at a sufficiently high rate of speed to cause the impeller blades to expel fluid in a finely atomized condition from one side of the trough, said expelled fluid being in the form of a stream which is substantially equal in width to the length of the trough and is substantially fan-shaped in vertical section, a transversely curved deflector blade substantially equal in length to the length of the trough, means for supporting said blade on said bearings for oscillatory movement in an arc substantially concentric with said impeller, the oscillatory movements of said blade causing the radial direction of discharge of said stream to be changed without substantially varying the concentration thereof, and means for continuously oscillating said blade through said arc during operation of the machine.

3. A dish and silverware washing, rinsing and drying machine comprising a housing, a shallow trough in the bottom thereof, alined bearings carried by the end walls of the housing above said trough, a bladed impeller journaled in said bearings, the blades being of proper length to dip into said trough, means for rotating said impeller at a sufficiently high rate of speed to cause the impeller blades to expel fluid in a finely atomized condition from one side of the trough, said expelled fluid being in the form of a stream which is substantially equal in width to the length of the trough and is substantially fan-shaped in vertical section, a transversely curved deflector blade substantially equal in length to the length of said trough, a ring journaled for rotation on each bearing, an arm attached to each ring and to an end of said deflector blade, said rings and arms supporting said blade for oscillatory movement in an arc concentric with the impeller, the oscillatory movements of said blade causing the radial direction of discharge of said stream to be changed without substantially varying its concentration, and power means connected to one arm of the blade for continuously oscillating the blade to cause the stream to be repeatedly discharged into all portions of the housing interior.

4. In a dishwashing machine the combination of a housing having a trough-shaped bottom for collecting fluid, a rotary impeller extending longitudinally of the housing and positioned to pick up fluid adjacent the bottom of the housing and to project the same upwardly through the said housing, a curved deflector coextensive with and partially surrounding said impeller for concentrating the stream thrown by the impeller and means for continuously oscillating said deflector through a substantial arc concentric with said impeller during operation of the machine whereby the fluid is concentrated in a zone which covers only a fractional portion of the interior of the housing and the thus concentrated zone of treatment continuously oscillated back and forth relative to the housing so that all portions of the housing are repeatedly included in the moving treatment zone.

5. In a dishwashing machine the combination of a housing having a trough-shaped bottom for collecting fluid, an elongated longitudinally extended rotary impeller mounted in said housing to pick up fluid adjacent the bottom thereof and project the same upwardly into the housing, a curved deflector partially surrounding said im-

peller and in such relation thereto as to cause the impeller to deliver a substantially uniform concentrated stream of fluid to a limited zone of treatment representing but a fractional portion of the interior of said housing and means for continuously oscillating said deflector through a substantial arc concentric with said impeller during operation of the machine whereby all portions of the interior of said housing are repeatedly subjected to the action of said substantially uniform concentrated stream.

6. In a dish and silverware washing, rinsing and drying machine, a housing adapted to concentrate a small quantity of fluid in the bottom thereof, a rotatable impeller for throwing finely subdivided fluid upwardly through the said housing, an oscillatable directional control deflector partially surrounding said impeller and arranged for oscillation through an arc concentric with the impeller and of a length adequate to effect controlled delivery of a substantially uniform concentrated stream to all parts of the housing during a single oscillation of said deflector and means for continuously oscillating said deflector through such arc during operation of the machine to thereby cause said substantially uniform concentrated stream to continuously traverse the interior of the housing in a succession of cycles.

7. A dish and silverware washing, rinsing and drying machine comprising a housing having a shallow trough in the bottom wall thereof, an impeller journaled in the housing above said trough having blades of a proper length to dip into said trough, means for rotating said impeller at a sufficiently high rate of speed to cause the impeller blades to expel fluid in a finely atomized condition from one side of the trough, said expelled fluid being in the form of a stream which is substantially equal in width to the length of the trough and is substantially fan-shaped in vertical section, a curved deflector associated with said discharge side of the trough and oscillatable through a substantial arc concentric with said impeller for changing the radial direction of discharge of said stream while maintaining it at a substantially uniform concentration, and power means for continuously oscillating said deflector through said arc.

8. A dish and silverware washing machine comprising a housing having a shallow trough in the bottom wall thereof, a bladed impeller journaled in the housing above said trough, the blades of said impeller being of proper length to dip into said trough, means for rotating said impeller at a sufficiently high rate of speed to cause the impeller blades to expel fluid in a finely atomized condition from the trough, said expelled fluid being in the form of a stream which is substantially equal in width to the length of said trough and is substantially fan-shaped in vertical section, a deflector oscillatably associated with said impeller and arranged to control the direction of discharge of fluid from said impeller blades, and means operable to continuously oscillate said deflector through an arc substantially concentric with said impeller to continuously change the direction of discharge of said stream without substantially varying its concentration.

9. In a dish washing machine, the combination of a housing having a trough-shaped bottom for collecting fluid, a rotary impeller extending longitudinally of the housing and having blades positioned to pick up fluid adjacent

the bottom of the housing and to project the same upwardly through the said housing, a horizontally elongated transversely curved deflector disposed adjacent the ends of said impeller blades for concentrating the stream thrown by the impeller, and means for continuously oscillating said deflector through a substantial arc concentric with said impeller during operation

of the machine whereby the fluid is concentrated in a zone which covers only a fractional portion of the interior of the housing and the thus concentrated zone of treatment is continuously oscillated back and forth relative to the housing so that all portions of the housing are repeatedly included in the moving treatment zone.

DONALD E. YOCHEM.
